FIG.1

FIG.2.

FIG.3.

FIG.4

INVENTOR.
LOUIS H. BERRY
BY: C. P. Enoch
ATTORNEY.

UNITED STATES PATENT OFFICE.

LOUIS H. BERRY, OF MINNEAPOLIS, MINNESOTA.

AUTOMOBILE-JACK.

1,303,240.

Specification of Letters Patent.

Patented May 13, 1919.

Application filed May 16, 1918. Serial No. 235,213.

To all whom it may concern:

Be it known that I, LOUIS H. BERRY, a citizen of the United States, and a resident of Minneapolis, in the county of Hennepin and State of Minnesota, have invented certain new and useful Improvements in Automobile-Jacks, of which the following is a specification.

This invention relates to that type of automobile jack designed to be permanently attached to the chassis of an automobile and is somewhat similar to that described in my co-pending application Serial #206,343 filed December 8, 1917 entitled Automobile jacks.

One object of my invention is to provide a simplified form of jack of the class described to be operated by hand power.

Another object of my invention is to provide a simplified construction of the rack used to swing the jack from a vertical to a horizontal position.

Another object of my invention is to provide means associated with the jack whereby the jack may be operated by the crank provided for the engine of the automobile or may be operated by the tire wrench.

With these and incidental objects in view, the invention consists of certain novel features of construction and combination of parts, the essential elements of which are hereinafter described with reference to the drawings which accompany and form a part of this specification.

In the drawings Figure 1 is a side view of my improved jack with parts broken away, Fig. 2 is a section taken on the line 2-2 Fig. 1 with part of the jack broken away and showing the axle in full, but with the outline of the driving bevel gear shown in the figure, Fig. 3 is an enlarged detail of the means provided for using a crank to operate the jack and Fig. 4 is a section taken on the line 4-4 Fig. 2.

A frame member 1, Fig. 2, preferably of cast steel is supported at 2 on the chassis of the automobile to which the device is applied.

This frame member is fashioned at 3 into a segment of a pinion and carries a tongue 4 to which is hinged by the bolt or pin 5 the entire lifting mechanism of the jack.

This lifting mechanism comprises a head 6 having projecting downwardly therefrom a tongue 7 Figs. 2 and 4, the head being hinged by the ears 8 to the pin 5.

Forming a part of, or suitably attached to,

the head 6 is plate 9 which with the ring 10 and cap 11 forms a housing for the bevel gear 12.

The bevel gear 12 is an integral part of the sleeve 13 which is fashioned into a nut 14 at its lower end, this entire piece preferably being in a shape of a casting with the bevel gear 12 cast in a core and the nut 14 machine cut.

A screw 15 suitably fastened to the foot 16 carries at its upper end a rack 17, the back face of which is in close relation with the flat face of the tongue 7.

Carried by the head 6 on a stud 18 on which it is journaled is a bevel gear 19 co-operating with the gear 12.

It is evident that if the gear 19 is rotated it will rotate the bevel gear 12 and the nut 14 forming a part of the same member will feed the screw 15 in or out of the sleeve 13 depending upon the direction the bevel gear is turned.

If the bevel gear 18 is turned so as to feed the screw 15 into the sleeve 13 it is also evident that the rack 17 will, toward the end of the upward motion of the screw, strike the pinion segment 3 and as the rotation of the bevel gear 19 is continued co-operate therewith and thus swing the suspended part of the jack upwardly to the left as viewed in Fig. 2.

The jack thus may be ordinarily swung to a horizontal position below the axle 20 which is its normal carrying position, or may be lowered to a vertical position and by the further operation of the bevel gear 19 used to elevate that portion of the chassis from which the jack depends.

Suitably fastened to or forming an integral part of the bevel gear 19 is a cup 21 Figs. 1 and 3 through which is passed a bolt 22.

A shaft 23 has a large aperture 24 therein through which the bolt 22 passes, and a washer 25, a spring 26, a washer 27 and a cotter pin 28 is provided for normally holding the shaft 23 in relation with the bolt 22 so as to eliminate looseness therebetween but it is evident that the shaft 23 may be turned at a considerable angle in any direction with the axis of the cup 21 thus forming a simplified universal joint for the rotation, by means of the shaft 23, of the bevel gear 19.

A hanger 29 attached at 30 to one of the rear spring bolts or any suitable location on

the chassis carries the opposite end of the shaft 23 loosely in the aperture 31.

Beyond the hanger 29 the shaft 23 carries a head 32 and a pin 33, the head 32 being fashioned so as to receive in operative relation the ordinary tire bolt wrench and the pin 33 is adapted to receive in operative relation the crank provided for the engine of the automobile.

10 It is evident that when the shaft 23 is turned either by means of the tire wrench or engine crank the bevel gear will be actuated causing the operation of the jack as hereto described and the shaft 27 will play in the 15 aperture 31, in the hanger 29 to allow the shaft to assume the necessary angular positions when the jack is swung from a horizontal to a vertical position and vice versa.

This angular movement of the shaft 23 20 may be small or large depending upon how close the axis of the bevel gear 19 is in line with the hinged pin between the frame 1 and the head 6, but the construction shown and described will take care of any reasonable alinement between these axes of revolution.

To prevent the rotation of the screw 15 when the bevel gear 12, and with it the nut 14, is revolved, the tongue 7, Figs. 2 30 and 4, comes in contact with the back face of the rack 17, causing the nut 14 to travel along the screw.

While I have described my invention and illustrated it in one particular design, I 35 do not wish it understood that I limit myself to this construction, as it is evident that the invention may be varied in many ways within the scope of the following claims:

1. In an automobile jack the combination 40 of a frame, a pinion sector carried thereby, a head hinged to said frame and having a depending tongue, a sleeve surrounding said tongue and rotatably associated with said head, a nut fashioned in the lower end of 45 said sleeve, a bevel gear fashioned exteriorly at the upper end of said sleeve, a foot having an upstanding screw projecting therefrom, a rack carried by the open end of said screw and adapted to impinge on and co-operate with said pinion sector during a portion of the travel of said screw in respect to 50 said nut and means for rotating said bevel gear.

2. In an automobile jack the combination 55 of a frame, a pinion sector carried thereby, a head hinged to said frame and having a depending tongue, a sleeve surrounding said tongue and rotatably associated with said

head, a nut fashioned in the lower end of 60 said sleeve, a bevel gear fashioned exteriorly at the upper end of said sleeve, a foot having an upstanding screw projecting therefrom, a rack carried by the upper end of 65 said screw and adapted to impinge on and co-operate with said pinion sector during a portion of the travel of said screw in respect to 70 said nut, and means for rotating said bevel gear, said tongue and said rack being so positioned as to prevent the rotation of the said screw.

3. In an automobile jack the combination of a frame member adapted to be suspended from an automobile chassis, a head hinged thereto and having a tongue depending therefrom, a sleeve rotatably mounted with 75 respect to said head and carrying on its upper end a bevel gear and on its lower end a nut, a screw for co-operating with said nut and having a foot on its lower end and a rack on its upper end, said rack being in 80 close position to said tongue to prevent rotation of said screw and a pinion sector carried by said frame member and adapted to co-operate with said rack near one end of 85 the travel of said rack for the purpose of swinging said head from a vertical to a horizontal position; a second bevel gear co-operating with first bevel gear and means for driving said second bevel gear.

4. In an automobile jack the combination 90 of a frame member adapted to be suspended from an automobile chassis, a head hinged thereto and having a tongue depending therefrom, a sleeve rotatably mounted with 95 respect to said head and carrying on its upper end a bevel gear and on its lower end a nut, a screw for co-operating with said nut and having a foot on its lower end and a rack on its upper end, said rack being in 100 close position to said tongue to prevent rotation of said screw and a pinion sector carried by said frame member and adapted to co-operate with said rack near one end of 105 the travel of said rack for the purpose of swinging said head from a vertical to a horizontal position; a second bevel gear co-operating with said first bevel gear and means for driving said second bevel gear, said means including an extended shaft having 110 a universal joint therein, the free end of which is loosely hung from a point on the chassis of the automobile to which the jack is applied and being formed at its extreme end to receive means for rotating said extended shaft.

LOUIS H. BERRY.
